WITNESS:

UNITED STATES PATENT OFFICE.

SEM ROSENTHAL, OF NEW YORK, N. Y.

CABINET.

Application filed April 29, 1924. Serial No. 709,871.

To all whom it may concern:

Be it known that I, SEM ROSENTHAL, a subject of King of Great Britain, residing at New York city, in the county of New York and State of New York, have invented new and useful Improvements in Cabinets, of which the following is a specification.

This invention relates to cabinets and is an improvement over the cabinet shown in my application Serial Number 604,332, allowed January 26th, 1924.

The principal object of the invention is to provide a cabinet of the type used by persons in subjecting their bodies to the action of hot air or vapor and which is formed of a plurality of parts which may be easily folded when not in use to permit the same to be carried about or stored away in a minimum amount of space.

A further object of the invention is to provide a foldable cabinet which may be set up by a single person to a point as to permit the person to enter the cabinet and insert his head through the top, after which a pair of pivoted plates may be moved without further assistance to fit around the neck and to seal the neck at the neck opening.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a perspective view of the cabinet in use.

Figure 2 is a vertical section view thereof.

Figure 3 is a top plan view.

Figure 4 is a perspective view of the cabinet in folded position.

Figure 5 is a detail perspective view of a slight modification.

Referring more particularly to the drawing, the reference numeral 10 designates the cabinet in its entirety, which includes a housing 11 into which the parts fold when in collapsed position. The housing is open at one side as at 12, and hinged thereto as at 13 is a bottom 14 which co-acts with the bottom of the housing and serves as a floor for the device. The side edges of the bottom are provided with upstanding flanges 15 which prevent the outward movement of

the side walls 16, which walls are hinged as at 17 to the side walls of the housing and which serve as an extension therefor. One of the side walls 16 has hinged thereto as at 18, a door 19 which may be swung outwardly when in a set-up position, the inward movement of the door being limited by a flange 20 on the other side wall. However, the door may be swung inwardly when folded up as the side wall having the flange 20 is first folded into the housing. The flange 20 carries a suitable catch 21 for locking the door in closed position, the catch being within reach of the person after entering the cabinet. Hinged as at 22 to each of the side walls 16 at the top thereof is a cover section 23, each section being of a size equal to one-half the width between the side walls and adapted to rest upon the top of the door 19 when in set-up position.

Each cover section is cut-away as at 24 and the cut-away portions co-acting to provide an opening 25 of a size to permit the head of a person to be inserted therethrough. In order to close the opening after the person's head has been inserted, I provide a pair of identical plates 26, each pivoted to the top of the housing as at 27 and provided with semi-circular recesses 28 which recesses permit the plate to fit snugly about the neck of a person whereby to seal the opening 25 to prevent the escape of vapor or heat at this point. The side walls 16, housing 11 and door 19 are each provided with a vertical standard or post 29 which posts support electric light bulbs 30 for the purpose of heating the air within the cabinet when a hot air bath is desired. Although there has been shown a means for supplying hot air, it is to be understood that steam might be introduced into the cabinet should a vapor bath be desired without departing from the spirit of the invention.

When not in use, the structure may be collapsed by folding the side walls 16 inwardly about their hinges, it being understood that the cover sections are first dropped down against the outside of the side walls and the door 19 swung inwardly against the side wall which supports it. After these parts have been folded into the housing, the bottom 14 is swung upward against the open end 12 of the housing where it may be locked to prevent the parts from accidentally moving out of the housing.

For strengthening purposes, the sides 16 and the housing may be provided with strips of angle iron 31. It will be noted that the housing is approximately one-third the width of the entire cabinet when the same is in a set up position and when in a folded position, the parts are all enclosed thereby only taking up one-third the amount of room as is required when in use.

10 In Figure 6, I have shown a slight modification of means for sealing the top of the cabinet about the neck of the user. In this form a pair of covers 32 are pivotally connected to the top of the housing 11 as at 33. Each cover comprises sections 34 and 35 hinged together as at 36. The sections 34 are provided with cut-out portions 37 for co-action with each other to provide a neck opening. When folded, the sections 34 and 35 overlie each other and are moved to a position overlying the top of the housing.

What is claimed as new is:—

1. A cabinet comprising a housing open at one side, a bottom hinged to said housing, side walls hinged to said housing, a door hinged to one of said side walls, cover sections hinged to the tops of said side walls and being cut-away to define an opening when in co-acting position for permitting the head of a person to be inserted therethrough, and a pair of pivoted plates carried by said housing for completely closing the opening after the head has been inserted therethrough.

hinged to the tops of said side walls and being cut-away to define an opening when in co-acting position for permitting the head of a person to be inserted therethrough, and a pair of pivoted plates carried by said housing for completely closing the opening after the head has been inserted therethrough.

2. A cabinet comprising a housing open at one side, a bottom hinged to said housing, side walls hinged to said housing, a door hinged to one of said side walls, means for limiting the outward movement of said side walls, cover sections hinged to the tops of said side walls and being cut-away to define an opening when in co-acting position for permitting the head of a person to be inserted therethrough, and a pair of pivoted plates carried by said housing for completely closing the opening after the head has been inserted therethrough, all of said hinged parts adapted to be folded into said compartment when not in use.

In testimony whereof I have affixed my signature.

SEM ROSENTHAL.
